UNITED STATES PATENT OFFICE

FERNAND PIRO, OF WOONSOCKET, RHODE ISLAND

SPINNING MACHINE

Application filed June 21, 1932. Serial No. 618,453.

This invention relates to a spinning machine, and is a continuation in part of my co-pending application Ser. No. 554,978, filed August 4, 1931.

One object of this invention is to provide a means for conserving the short fibers of the yarn by pressing them into the yarn and avoiding the loss of these fibers as lint or waste.

Another object of this invention is the provision of means by which less cleaning of the waste collecting rolls will be required.

Another object of the invention is to provide a more uniform thread, thus reducing the lumps or bunches and thin places formed.

Another object of the invention is to provide a heavier thread for a given length which emanates from the spinning machine.

A further object of this invention is the provision of a guide so arranged as to size and shape that it may be located between the front roll and the next adjacent pair of carrier rolls and supported in this position without interfering with the removal of the rolls for cleaning.

A still further object of the invention is the provision of a movable guide which will adjust itself to the travel of the yarn and by centralizing itself with respect to the general direction of the travel of the yarn will prevent kinking of the yarn and afford a better yarn than where the yarn must be drawn at sharp angles with reference to a fixed guide.

With these and other objects in view the invention consists of certain novel features of construction, as will be more fully described, and particularly pointed out in the appended claims.

In the accompanying drawings:

Fig. 1 is a top plan view of a portion of the spinning machine with certain parts unrelated to the invention omitted for the sake of more clearly illustrating the parts having more particularly to do with this invention.

Fig. 2 is a sectional view of the frame on substantially line 2-2 of Fig. 1, showing the relative arrangement of the rolls.

Fig. 3 is a sectional view showing in de-

tail on a larger scale the guide and its mounting between the front rolls and a pair of rolls just back of the front rolls.

Fig. 4 is a detailed view of the member which is positioned between the rolls and showing the guides as mounted thereon.

Fig. 5 is a perspective view of the member alone with the guides detached therefrom.

Fig. 6 is a perspective view of the movable yarn guide.

Fig. 7 is a perspective view of the yarn guide shown in Fig. 6 mounted on a fragmental portion of the support member.

Fig. 8 is a section on line 8-8 of Fig. 7.

Fig. 9 is a perspective view of an attaching yoke for supporting the elongated member of Fig. 5 in position.

Fig. 10 is a central sectional view through the structure shown in Fig. 9 with the bar or guide supporting member shown in Fig. 5 in secured position.

Fig. 11 is a perspective view of a modified construction showing fragmentarily the over-arm and a modified form of guide of the non-movable or non-traveling type.

Some types of spinning such as mule spinning used for the better grades of yarn comprise a movable carriage and a stationary part of the machine, with relation to which the carriage moves. In this stationary portion of the machine there is mounted a plurality of pairs of rolls traveling at different relative surface speeds between which the yarn extends prior to its being drawn out by the movable carriage.

The pairs of rolls so employed are positioned with their centers as close together as possible, consistent with practical operation, thus bringing their surfaces closely adjacent and just clearing. It is of course recognized that the smaller the diameter of the rolls the closer together may be the points of contact of the two pairs of rolls. There is, however, a limit to the minimum diameter which can be had for the rolls, as these rolls must be sufficiently strong to withstand certain strains which are placed upon them in use; such as the pull of the yarn, the weight on the rolls for nipping the yarn, and the driving of the rolls from one end of the machine, which may

85

90

95

100

extend for a considerable length. The surfaces of the pairs of rolls must also have a sufficient clearance to permit any lint, which is gathered by the roll from the yarn, to pass between the rolls.

These features limiting the distance between the nips of the pairs of rolls are particularly important with reference to the front pair and next immediate adjacent pair of rolls. Thus the space which is provided between these two pair of rolls is very limited and will not permit a support or the like extending between the pairs of rolls, however I have provided a guide which may be located 10 within this minimum space and be supported from the overarms between the working surfaces of the roll and which arms support the bearings for the different rolls and the guide which I provide does not interfere with the 15 removal of the rolls, for the piecing up of broken ends, should such broken ends occur. I have also found that where a guide is employed which cannot move with reference to the 20 position of the travel of the yarn over the roll or shift with the travel of yarn that it is desirable to provide a movable guide which will adjust itself to this center and thus accommodate itself to machines in which adjustment of the rod between the front pair of 25 rolls and next adjacent pair of rolls cannot be had; and the following is a detailed description of the present embodiment of this 30 invention illustrating the preferred means by which these advantageous results may be accomplished.

The drawings show the invention as applied in a mule spinning frame in which 9 is the 35 stationary frame part of the mule spinning machine upon which there is mounted a plurality of bearing blocks 10 supporting the lower driven rolls 11, 12, 13, 14 and 15 which extend a considerable length and are formed with reduced portions between their working 40 surfaces as shown in Fig. 1. These are each 45 suitably driven from one end of the machine in the usual manner. Overarms 16 are provided at spaced intervals along the length of the machine upon which blocks 17 are secured in adjusted position and each block is provided 50 with a groove 18 in which the reduced end portions of the upper rolls 19, 20, 21, 22 and 23 are supported and rest by their own weight upon the corresponding lower rolls. The roll 19 is of large diameter to press with 55 sufficient weight upon the lower roll 11, while the upper roll 23 of the front pair of rolls is also of large diameter for this same purpose, and in some instances additional weight is provided upon the upper front roll by means 60 of the arm 24 pivoted as at 25 at the back of the machine and pressing upon the front roll 23 by its own weight and also through links 25, 26, lever 27 and weight 28 which may be 65 adjusted along the lever 27 to rest in any suitable notch 29.

The remaining rolls act as slip rolls and carry the yarn along between nips. Clearer roll 30 for the roll 23 and clearer 31 for the roll 10 are provided to pick up any waste or accumulation, or short fibers on either of 70 these rolls which may collect. The clearer 31 is held in engagement with the lower roll 15 by a member 32 pivoted on shaft 36 and weighted by its enlarged end 33. The clearer block 34 engages the roll 14 and is similarly 75 held in engagement by a lever 35 pivoted as at 36 and forcing the block 34 into engagement with the roll 14 by reason of its enlarged end 37 forming a weight.

As the yarn travels through the rolls the 80 curl of the fibers often fray and form a waste which collects upon the rolls such as the front rolls 15 and 23 or the next adjacent set of rolls 14 and 22 which it is the purpose of the clearers to pick up, and in order that these 85 fraying fibers may be forced back into the yarn by an ironing process I have supported an elongated member 40 in the form of a rod or the like between the pairs of rolls 14 and 22 and 15 and 23 which must be of very thin 90 and small construction by reason of the constricted space between these pairs of rolls which run with their surfaces just clear of each other. And in order to support this 95 elongated member or rod 40 from the overarm 16 I provide a yoke 41 having an opening 42 to receive the overarm and be held in adjusted position thereon by a set screw 43. This yoke or support has the elongated member or rod secured thereto in any suitable or 100 desired manner such as by a rivet 44 as shown in Fig. 4.

The elongated member or rod 40 is notched at intervals as at 45 and in certain of these notches I have slidably supported a guide 46 which is shown in Fig. 6 in perspective and consists of a body 51 having a flaring notch portion 47 to receive the yarn that is drawn from the back to the front of the machine which serves to condense and iron the fibers 105 or press them back into the strand or yarn. This guide is provided with arms 50 having slots 47a therein which receive the portions 48 adjacent each side of the notch 45 and slidably mount the guide in position on the rod, permitting it freedom of sliding movement limited only by the sides 49 of each of the slots.

The arm portions 50 of this guide are retained against lifting movement by pins 52 110 at either side of the notch which extend over the arms 50 and prevent the guides from being lifted from its assembled position with the rod. By reason of this construction of guide and its sliding movement on the elongated member or rod, the same will centralize 115 itself with reference to the location of the yarn as it moves over the roll and thus prevents any sharp kinks or twists in the yarn and also will, if sufficient pressure is exerted 120 125 130

upon it, slide laterally and follow the transverse motion of the yarn which is given it to prevent wear in one place on the draft rolls. It is important that the guide be permitted to slide to centralize itself with respect to the yarn as the rod or elongated member cannot be adjusted after it is positioned in the machine and slight variations may occur in each of the different positions of the run of the 10 yarn which it is desired should be accommodated.

Certain notches 53 are also placed in the rod to accommodate the hand for lifting the adjacent upper roll 22 from position, as may 15 sometimes be required in the operation of the machine.

In Fig. 9 I have illustrated a support yoke 54 which is slotted as at 55 to receive the thin elongated member or rod 40 which may 20 be riveted in such position as shown at 56 in Fig. 10.

I have also illustrated in Fig. 11 a modified construction of guide having a yoke 57 which is mounted on the overarm 16 and a 25 rod 58 formed integral with the yoke 57. This arm is provided with flaring notches 59 to serve as guides. In this instance, however, there is no movement or travel permitted of the guide to accommodate itself to the travel 30 of the yarn or to prevent sharp angles as provided for in the construction directed above.

The foregoing description is directed solely towards the construction illustrated, but I 35 desire it to be understood that I reserve the privilege of resorting to all the mechanical changes to which the device is susceptible, the invention being defined and limited only by the terms of the appended claims.

I claim:—

40 1. In a spinning machine, a plurality of pairs of rolls between which the yarn travels, including a pair of front rolls and a pair of rolls back of the front rolls, an elongated member supported between said pairs of rolls and having a notch in its upper edge, a yarn guide in said notch with portions engaging the front and rear surfaces of said member permitting it to slide along said member.

45 2. In a spinning machine, a plurality of pairs of rolls between which the yarn travels, including a pair of front rolls and a pair of rolls back of the front rolls, an elongated member supported between said pairs of rolls and having a notch in its upper edge, a yarn guide in said notch with portions engaging the front and rear surfaces of said member permitting it to slide along said member and follow the traverse of the yarn along the roll, 50 pins mounted in said member at either side of said notch and portions on said guide extending beneath said pins to prevent removal of said guide from said member while permitting sliding movement thereof along 55 said member.

3. In a spinning machine, a plurality of pairs of rolls between which the yarn travels, including a pair of front rolls and a pair of rolls back of the front rolls, a relatively thin elongated member supported between 70 said pairs of rolls and having a notch in its edge, a guide slotted on its under surface and receiving said member and slideable therealong, said guide setting into said notch and limited in its movement by the edges of said 75 notch.

4. In a spinning machine, a plurality of pairs of rolls between which the yarn travels, including a pair of front rolls and a pair of rolls back of the front rolls with their surfaces 80 closely adjacent and just clearing the front rolls, an overarm extending from the back of the machine, and an elongated member located between the front rolls and the next pair of rolls, a yarn guide slideable along said member and means for supporting said member from said overarm.

5. In a spinning machine, a plurality of pairs of rolls between which the yarn travels, 90 including a pair of front rolls and a pair of rolls back of the front rolls with their surfaces closely adjacent and just clearing the front rolls, an overarm extending from the back of the machine, and an elongated member located between the front rolls and the next pair of rolls, a yarn guide slideable along said member and means in substantially the plane 95 of said overarm for supporting said member from said overarm.

6. In a spinning machine, a plurality of pairs of rolls between which the yarn travels, including a pair of front rolls and a pair of rolls back of the front rolls with their surfaces closely adjacent and just clearing the 100 front rolls, said rolls having reduced portions between their working surfaces, yarn guide supporting means located between said pairs of rolls means extending thru said reduced portions for supporting said yarn guide supporting means, and a yarn guide extending longitudinally along and slidably mounted on said yarn guide supporting means to follow the traverse of the yarn along said rolls.

7. In a spinning machine, a plurality of pairs of rolls between which the yarn travels, including a pair of front rolls and a pair of rolls back of the front rolls with their surfaces closely adjacent and just clearing the 115 front rolls, said rolls having reduced portions between their working surfaces, an elongated member located between said pairs of rolls, means extending thru said reduced portions for supporting said elongated member, a yarn guide extending longitudinally along and slidably mounted on said member and provided with a notch to receive the yarn, and stop means on said member to limit the movement of the guide.

8. In a spinning machine, a plurality of 130

pairs of rolls between which the yarn travels, including a pair of front rolls and a pair of rolls back of the front rolls, said rolls having reduced portions between their working surfaces, a relatively thin elongated member located between said pairs of rolls, means extending thru said reduced portions for supporting said elongated member, and a guide

extending longitudinally along and slotted on its under surface for receiving said member whereby it is slidable therealong in response to tendency towards lateral movement of the yarn.

In testimony whereof I affix my signature.
